I claim the ornamental design for an interior car mat, as shown and described.

DESCRIPTION

FIG. 1 is a perspective view showing my new design for an interior car mat.

FIG. 2 is a front plan view thereof.

FIG. 3 is a rear plan view thereof.

FIG. 4 is a top plan view thereof.

FIG. 5 is a bottom plan view thereof.

FIG. 6 is a left-side plan view thereof.

FIG. 7 is a right-side plan view thereof; and,

FIG. 8 is a top view thereof, shown in environmental use. The broken lines represent unclaimed subject matter and form no part of the claimed design.

The shading lines shown in the drawings represent the approximate three-dimensional contour of the design, and are not intended to indicate surface decoration.
